Inventor,
William Redford Mulock.

George A. Hutchinson
Attorney.

UNITED STATES PATENT OFFICE.

WILLIAM REDFORD MULOCK, OF WINNIPEG, MANITOBA, CANADA.

NOISE-REDUCING TYPEWRITER PLATEN.

1,415,844.

Specification of Letters Patent.

Patented May 9, 1922.

Application filed September 3, 1921. Serial No. 498,270.

To all whom it may concern:

Be it known that I, WILLIAM REDFORD MULOCK, a subject of the King of Great Britain, and resident of Winnipeg, in the 5 Province of Manitoba, Dominion of Canada, have invented certain new and useful Improvements in Noise-Reducing Typewriter Platens, of which the following is a full, clear, and exact specification.

10 This invention relates to platens for type-writing machines and has for its object to provide a noise-reducing platen of simplified and improved construction.

A special aim of the invention is to insure 15 the production of clear impressions from the type, as well as the deadening of the sound resulting from said type striking the platen. Another object is to dispense with the complicated and expensive constructions heretofore employed for the purpose mentioned, and to produce a platen of very simple and 20 inexpensive construction which will give superior results. Further objects will appear as the description proceeds.

25 The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

35 Figure 1 is a longitudinal central section of a roller platen constructed substantially in accordance with this invention.

Figure 2 is a transverse section taken on the line II—II of Figure 1.

40 Figure 3 is a front elevation of a stationary cylindrical platen frame similar to that disclosed in my Patent, No. 1,382,218, dated June 21, 1921, but showing the striking surface of the platen strip covered with celluloid, and

45 Figure 4 is a transverse section of the platen frame illustrated in Figure 3 taken on the line IV—IV thereof.

Referring first to Figures 1 and 2 of the 50 drawings, 1 designates the usual shaft which extends centrally through the roller platen and has milled knobs on its ends. The platen is built upon a small supporting sleeve or tube 3 which fits snugly on the 55 shaft 1 and may be secured to turn therewith

in any suitable manner as by the set screws 4 in the projecting end portions of said tube. The core or body portion 5 of the platen is made of soft rubber which is preferably formed in a solid cylindrical piece fitted 60 around the tube 3 with which it is designed to turn. Struts or projections 6 may be formed on said tube at suitable intervals to hold the soft rubber core in place thereon and prevent it from losing its shape. 65

On the outside of the cylindrical soft rubber core 5 there is a surface member 7 of thin celluloid or other similar substance having a smooth outer face of sufficient hardness to produce clear impressions under the impact 70 of the type without being effected thereby, and of sufficient strength to maintain an even printing surface. Said surface 7 may be formed as an integral tube fitted closely around the soft rubber core 5 so as to turn 75 therewith as best illustrated in Figure 2, but said surface may be built up of separate pieces joined together or fastened to the outside of the core in any suitable manner.

Referring now to Figures 3 and 4, the stationary platen frame 8, illustrated therein, is mounted on a central shaft 9 having milled knobs 10 at its ends. A platen strip or core 11 of soft rubber is mounted in a horizontal slot 12 in the front of the skeleton frame 8, said platen strip being preferably set in a supporting clip 12, Figure 4, which is cushioned on springs 13 supported on a sleeve 14 loosely mounted on the shaft 9, but any other means for cushioning said 90 strip 11 may be employed without affecting the principle of the invention. The platen frame 8 also carries paper feeding rollers 15 similar to those illustrated and described in my Patent No. 1,382,218, hereinbefore mentioned.

The printing face of the platen strip or core 11 is covered with a surface member 16 of thin celluloid or other suitable material of the same properties as the surface 7 100 on the roller platen already described in connection with Figures 1 and 2 of the drawings. This surface member 16 may be secured to the soft rubber platen strip 11 in any suitable manner, as by an adhesive, and the edges thereof may be bent to grip the upper and lower faces of said strip, as illustrated in Figure 4, for more securely holding said surface member in position.

In either of the forms of platens herein 110

illustrated and described, the soft rubber core or body portion, which constitutes the sole direct support for the hard surface member, serves to deaden the sound which is usually produced by the striking of the type upon platens of ordinary constructions. The thin surface 7 or 16 of celluloid, or other similar material, insures clear impressions being made when the type strikes either of the present forms of platens but, because of the solid formation of the soft rubber core, such hard surface member will not appreciably increase the noise produced.

I claim:

- 15 1. In a typewriter platen, the combination with a supporting member, of a thin surface member of hard material, and a soft rubber core extending from said supporting member to said surface member.
- 20 2. In a typewriter platen, the combination with a supporting member, of a thin celluloid surface member, and a soft rubber core extending from said supporting member to said surface member.
- 25 3. In a typewriter platen, the combination with a supporting member, of a thin surface member of hard material, and a soft rubber core extending from said supporting member to said surface member and constituting

the sole direct support for the latter member.

4. In a typewriter platen, the combination with a supporting member, of a thin tubular surface member of hard material, and a soft rubber core surrounding said supporting member and extending therefrom to said surface member.

5. In a roller platen for typewriter machines, the combination with a central supporting member having projections thereon, of a soft rubber core fitted around said supporting member and retained in position thereon by said projections, and a thin covering of hard material substantially as described surrounding said core for the purpose specified.

6. In a roller platen for typewriter machines, the combination with a central supporting member, of a soft rubber core fitted around said supporting member, there being projections on said member embedded in said core for holding the latter in place, and a thin covering of hard material substantially as described surrounding said core for the purpose specified.

In testimony whereof I have signed my name to this specification.

WILLIAM REDFORD MULOCK.
